UNITED STATES PATENT OFFICE.

GEORGE H. BENJAMIN, OF NEW YORK, N. Y., ASSIGNOR TO THE SAFETY CAR HEATING AND LIGHTING COMPANY, OF NEW JERSEY.

APPARATUS FOR HEATING RAILWAY-CARS.

SPECIFICATION forming part of Letters Patent No. 398,487, dated February 26, 1889.

Application filed November 30, 1887. Serial No. 257,909. (No model.)

To all whom it may concern:

Be it known that I, GEORGE H. BENJAMIN, of the city, county, and State of New York, have invented certain new and useful Improvements in Apparatus for Heating Railway-Cars, of which the following is a specification.

My invention comprehends the employment of steam derived from any suitable source external to the car to be heated, as the primary source of heat, and of air heated by such steam and transmitted throughout the interior of the car as the secondary or indirect source of heat.

15 My invention likewise comprehends the employment, in combination with the radiator, induction-pipe, and air-flues, of a device for filtering the air in its passage to the interior of the car.

20 My invention likewise relates to various details of construction, which will hereinafter be more fully set forth, and succinctly specified in my claims.

25 In the accompanying drawings, which illustrate my invention, similar letters of reference indicate like parts.

Figure 1 is a longitudinal vertical section of a railway-car, showing the arrangement of my device when placed therein. Fig. 2 is a 30 plan view of the interior of a car. Fig. 3 is a detail in perspective of one of the air-flues. Fig. 4 is an elevation of a radiator such as I desire to employ. The face of the radiator is shown as broken away, to illustrate the interior construction of the radiator. Fig. 5 is a 35 top view of the radiator, also broken away to show the top of the radiator-pipes.

40 In the drawings, A indicates a railway-car, and B a steam-pipe, carried under the car or within the car, its position not being material, and this pipe adapted to be connected through suitable couplings between the cars with the source of steam.

The pipe B, when two or more cars are connected, forms an unbroken passage for steam throughout the entire length of the train, and the steam employed in the several cars is carried into and connected to the apparatus within each through the medium of a pipe—50 such as C—and in this pipe I arrange a controlling-valve, D, which valve may be adapted

to be operated from the interior of the car, if desired.

Arranged along each side of the car are the main air-flues E, and extending inward toward the center of the car are the lateral air-flues F, preferably arranged as shown in the plan, Fig. 2—that is to say, the lateral flues are arranged under alternate seats on opposite sides of the car. By this arrangement of flues 55 an excellent distribution of the heated air transmitted through the flues is accomplished.

At each end of the car, but on opposite sides, I arrange a radiator, G, which may be of any desired construction, preferably of 60 that kind wherein the surfaces of the radiator-pipes are provided with projections, thereby giving a large radiating-surface and serving to break up the incoming current of air in its 65 passage over the radiator. The radiator proper I inclose within a casing, H, and this casing I connect through the pipe I with the flue E on one side of the car. In certain cases it may be necessary to use but a single radiator, in which case the flue E is carried around the 70 car, returning to the radiator. In the top of the casing of the radiator I arrange a register, J, and also place similar registers, K, in the front of the radiator.

The air to be heated is preferably carried 75 into the car by means of an induction-flue, L, the upper end of which is provided on the outside of the car with a hood, M, in which is a pendent valve, N. O is a damper in the pipe L, by which the quantity of air admitted 80 may be regulated. The incoming currents of air traversing the pipe L pass over a basket, P, arranged in the bottom of the flue L and at a point lower than the base of the radiator-pipes G. Within this basket, which is 85 preferably made of wire and which is located in a suitable vessel, Q, I place a quantity of any material, preferably fibrous material, which will serve to pick up the particles of dust in the air and yet not interfere with the passage of the air to any extent. Fine-shaven wood, or what is known as "excelsior," I find to be well adapted for the purpose. In practice I find this material to give the best results when wet, and in order to provide for the 90 moisture of the material I arrange a pipe, R, under and communicating with the radiator 95

G, and carry the condensed water from the radiator and discharge it through the sprinkler S over the material in the basket P.

In order to provide for any surplus of condensed water, I arrange a waste-pipe, T, adapted to discharge under the car.

U represents an air-damper arranged in one end of the radiator-case, and which serves a double purpose, first, to allow the ingress of air from the floor of the car, and consequently at its lowest point when the car is at rest and but little air entering through the pipe L, and, secondly, to provide an opening through which the basket P may be removed in order 15 to replace its filling, or for other purpose.

The operation of my device will be readily understood. When the car is in motion, the air enters through the hood M, passes downward through the pipe L over the material in 20 the basket P, and thence upward, as heated, over the radiator-pipes D, and from the radiator by the pipe I to the main flue E, and thence through the lateral air-flues F outward to the interior of the car. If desired, the 25 lateral flues may be provided with a damper, V, by which the air-exit from the lateral flues may be closed, more or less, and thus cause the air to be equally diffused throughout the car.

When a car is at rest, a much smaller portion of air will enter through the pipe L 30 than when the car is in motion, and the damper U may then be opened, as also the registers J or K, or both, as required.

I wish it understood that I do not limit myself to the various details of construction 35 shown in the drawings and described in the

specification, as many changes may be made therein without departing from the intent of my invention.

I claim as my invention—

1. In a railroad-car, the combination of a pipe or diffusing air-flue within the car provided with lateral flues, a steam-radiator, a pipe for connecting said radiator with the source of steam, a casing for said radiator, with 45 which the diffusing air-flue is connected, an air-induction pipe communicating with the external air and said casing, an air-filter for said induction-pipe, a pipe arranged to moisten the filter by the water condensed in the radiator, and a waste-pipe leading from the filter, substantially as set forth.

2. In a railroad-car, the combination of a pipe or diffusing air-flue within the car provided with lateral flues, a steam-radiator, a 55 pipe for connecting said radiator with the source of steam, a casing for said radiator, with which the diffusing air-flue is connected, an air-induction pipe communicating with the external air and said casing, an air-filter for 60 said induction-pipe, a pipe arranged to moisten the filter by the water condensed in the radiator, a waste-pipe leading from the filter, and an air-damper, U, in one end of the radiator for admitting air and for placing the 65 filter-basket P, substantially as set forth.

In witness whereof I have hereunto set my hand this 29th day of November, 1887.

GEO. H. BENJAMIN.
